US00D401763S

United States Patent

[19]

Wolff

[11] Patent Number: Des. 401,763

[45] Date of Patent: Dec. 1, 1998

[54] STORAGE CONTAINER

[75] Inventor: Stacy L. Wolff, Houston, Tex.

[73] Assignee: Rubbermaid Incorporated, Wooster, Ohio

[] Term: 14 Years

[21] Appl. No.: 57,723

[22] Filed: Jul. 30, 1996

[51] LOC (6) Cl. 03-01

[52] U.S. Cl. D3/273; D3/302; D9/424

[58] Field of Search D3/272, 273, 302; D9/420, 423, 424, 425; 206/501, 503, 508, 518, 505; 220/334, 335, 337, 339

[57]

CLAIM

The ornamental design for a storage container, as shown and described.

DESCRIPTION

FIG. 1 is a top front perspective view of a storage container showing my new design;

FIG. 2 is a top plan view thereof;

FIG. 3 is a front elevational view thereof;

FIG. 4 is a right side elevational view thereof; the left side elevational view being a mirror image; and,

FIG. 5 is a rear elevational view thereof.

The bottom of the storage container forms no part of the claimed design.
